UNITED STATES PATENT OFFICE.

JOHN BIRCH NEESHAM, OF GLASGOW, SCOTLAND.

MOLDING-MACHINE FOR FOUNDRY USE.

1,318,101.

Specification of Letters Patent.

Patented Oct. 7, 1919.

Application filed January 18, 1919. Serial No. 271,898.

To all whom it may concern:

Be it known that I, JOHN BIRCH NEESHAM, a subject of the King of Great Britain, residing at Glasgow, Scotland, have 5 invented certain new and useful Improvements in Molding-Machines for Foundry Use, of which the following is a specification.

This invention relates to molding machines for foundry use, of the jarring type and having a turn-over table, of the class in which the mold is raised by fluid pressure and is allowed to fall by gravity the mold being formed about the pattern by 15 jarring or jolting.

Under this invention, the molding machine comprises a molding table and a turn-over table, fluid pressure cylinders being connected with the tables, and valve means 20 being provided for controlling the supply of fluid under pressure to the cylinders, whereby the raising and lowering of the tables and the jarring operation are performed. The turn-over table is manipulated by means of worm gearing.

There is also provided in connection with the valve controlling the jarring operation, a pilot valve and a by-pass, the construction and arrangement being such that the action 30 of the jarring valve is controlled by the pilot valve so that the necessary volume of pressure fluid is admitted for jarring purposes, while the jarring valve can also be controlled or locked by the pressure fluid 35 at the proper times, for example, when drawing a pattern, and its movement prevented in the event of the supply of fluid to the pilot valve being inadvertently or accidentally turned on, which would, in ordinary circumstances, cause the molding table 40 to precipitately fall.

On the drawings:—

Figure 1 is a side view of the improved molding machine.

45 Fig. 2 is an end view thereof and showing, in dotted lines, the turn-over table D in the raised position.

Fig. 3 is a side view, partly in section, and Fig. 4 a plan view of the improved valve 50 mechanism fitted to a molding machine such as illustrated at Figs. 1 and 2, and

Fig. 5 is a vertical section, to an enlarged scale, of the valve mechanism with the valve a removed.

55 In carrying out the invention, as illustrated, A is the usual main fluid pressure

cylinder containing the ram for raising and lowering the molding table B. B¹ are cushioning impact surfaces on which the molding table normally rests. C are fluid pressure cylinders containing the rams for raising and lowering the turn-over table D. E is the worm gearing for turning over the turn-over table D. F is the jarring valve mechanism for controlling the jarring operation. G is the pilot valve mechanism. H is the by-pass, and I is the pipe connection thereto for the fluid under pressure. J is the pipe connection to the pilot valve mechanism G while K is the pipe connection to 70 the main cylinder A through the jarring valve chest b.

The pattern is secured to the turn-over table D and the mold box is secured over the pattern and filled with sand as usual. The 75 jarring operation is performed by raising the molding table B and turn-over table D, to the desired extent, by means of the ram in the cylinder A. When the cylinder A is opened to exhaust, both tables fall by 80 gravity and thus produce the jarring action, which action is continued or repeated as long as is considered necessary or desirable and is hereinafter fully described.

When the jarring operation is completed 85 the turn-over table D with the mold thereon is raised to its full extent by admitting fluid pressure to the cylinders C and it is then turned over or rotated by means of the worm gearing E operated by the hand-wheel 90 E¹. The molding table B is then raised by admitting pressure fluid to the cylinder A, until it touches the molding box depending from the turn-over table D and the box is then detached. The molding table B is then 95 allowed to move downward with the mold thereon, either by leakage around the ram, or by opening the usual exhaust valve, while the suspended pattern is still secured to the turn-over table D. The turn-over table D 100 may now be righted, by means of the worm gear E, in readiness to return to its original position for again receiving the molding box and the sand for the next molding operation, the mold on the molding table B being meanwhile removed by any suitable means.

A control rod a⁴ (see Fig. 2) is secured to the lower surface of the molding table B and it projects downward so that its lower 110 end almost contacts with the bolt head at the upper end of the pilot valve k (see Fig.

3). The function of this rod will be hereinafter explained.

The mechanism for controlling and locking the jarring valve by the pressure fluid, 5 at the proper times, in the event of the supply of fluid being inadvertently or accidentally turned on to the pilot valve, will now be described.

The jarring valve *a* (shown in Fig. 3 but 10 omitted in Fig. 5) which is fitted in a suitable chest *b*, is preferably of cylindrical formation and comprises an upper and a lower part connected together by a neck *c* of smaller diameter, said neck forming a circumferential groove in the valve. The valve 15 chest is provided with ports or openings, *d*, *e*, *e*¹, *f*, (Fig. 5) the port or opening *d* communicating with the source of fluid pressure through the by-pass *H*, the ports or 20 openings *e*, *e*¹, communicating with the main cylinder *A*, and the exhaust opening *f* with the atmosphere. Another port or opening *m*¹ is provided and communicates with the pilot valve *k*. The jarring valve *a* is also 25 provided, at its lower end, with a working face *g* which rests upon a suitable seat *g*¹ formed in the lower end of the valve chest *b* so as to make a fluid-tight joint therewith.

30 The upper end of the jarring valve *a* is of larger diameter and is preferably provided with a cup leather *a*¹, or equivalent packing means, for making a fluid-tight joint, and a spiral spring *a*², is fitted between the 35 top of the valve and the cover of the valve chest *b*. The extent of movement of the valve *a* can be regulated by the screw *a*³ which passes through the valve chest cover. The opening *r* in the valve chest cover 40 admits lubricant to the interior for lubricating the valve *a*.

The valve chest *b* is provided with a flange *h* to which is connected a flange *i* of the pilot valve chest *j*.

45 The pilot valve *k*, fitted in the chest *j*, is preferably in the form of a spindle made hollow at its lower end and communicating with the fluid pressure supply by means of the pipe *J*. The pilot valve *k* is made, at 50 its center, with a slot *k*¹, running lengthwise therein into which projects a screwed pin *k*², operating through the valve chest *j* thereby limiting the upward and downward movements of the valve. The valve 55 *k* is also made hollow at its lower end for the reception of a hollow screwed fastening *n* by means of which the cup leather *o* is secured in place. Suitable ports or passageways *m*, *m*¹, *m*², *m*³, *m*⁴, are also formed in 60 the valve *k* and valve chest *j*. The port *m* in the valve *k* serves to admit fluid pressure to the interior of the jarring valve chest *b* by means of the communication port *m*¹ for operating or raising the jarring valve 65 *a*, which admission takes place when the two

ports are brought into line by the upward movement of the valve *k*. When the valve *a* is raised the exhaust port *e*¹ from the main cylinder *A* is opened and the pressure fluid exhausts from the cylinder *A* thereby causing the molding table *B* to instantaneously fall and produce the jolt or jar. The circumferential passageway *m*², formed in the valve *k*, provides a means of communication 70 between the port *m*¹ and the exhaust port *m*² so as to allow the valve *a* to fall thereby putting the main cylinder into communication with the fluid pressure pipe by means of the port *e*. The passageway *m*⁴ serves for the admission of lubricant to the valve chest, 80 by means of the pipe connection *p*.

The upper end of the pilot valve *k*, which projects through the valve chest *j*, is preferably provided with a cap or cover *k*³ which serves as a sand guard for preventing 85 particles of sand, falling from the molding table, lodging on the upper part of the chest *j* and interfering with the operation of the valve *k*.

The by-pass *H* is connected to the upper 90 part of the jarring valve chest *b* by means of the opening *d* and, at its other end, to the fluid pressure supply pipe *I* which communicates with the lifting cylinders *C*. When the lifting cylinders *C* raise the 95 turn-over table *D* the pressure fluid also passes, by way of the by-pass *H* and the opening *d* to the interior of the upper part of the jarring valve chest *b* thereby creating a pressure therein and locking and 100 jarring valve *a* on its seat.

By locking the jarring valve on its seat in the manner described, said valve is prevented from opening to the exhaust while a mold is being lowered away from the pattern, and lifting and leakage is prevented, moreover, any accidental dropping of the main table, through the opening of the valve or cock admitting pressure fluid to the pilot valve *k*, is also prevented, as during the operation of drawing the mold the pilot valve remains out of action.

While I prefer to standardize the stroke of the jarring valve *a*, that is to say, to have a certain length of stroke in accordance with the size of the machine, I may in some cases, so construct the valve *k* that the stroke can be varied. In order to do this I make the pilot valve *k* with an additional port *m*⁵ which port can be brought into line with the communication port *m*¹ by unscrewing the screw pin *k*² from the slot *k*¹ and partially rotating the valve *k* until the other slot *k*⁴ formed therein comes into line with the point of the pin *k*². When this takes place 115 120 125 130 the pin *k*² can be once more screwed into position in the slot *k*⁴. As the slot *k*⁴ is shorter than the slot *k*¹ the stroke of the valve *k* is limited accordingly while the port *m*⁵ will admit fluid pressure to the interior of the 130

jarring valve chest b , by means of the communication port m^1 .

The sequence of operations is as follows:—

- 5 Pressure fluid is first admitted to the pilot valve k by means of the pipe J thereby raising the valve k until it contacts with the lower end of the pilot valve control rod a^4 . Pressure fluid is now admitted to the valve chest b by the pipe K to allow of same passing by means of the port e to the underside of the piston in the main cylinder A thereby raising the molding table B and the control rod a^4 thus releasing the pilot valve k which, having pressure fluid underneath it, resumes its upward movement until the lower end of the slot k^1 contacts with the screw pin k^2 when it stops. In this position the port m comes opposite the port m^1 thus admitting pressure fluid to the underside of the upper part of the jarring valve a and forcing said valve upward against the lower end of the screw a^3 in the cover so as to open the exhaust port e^1 in the valve chest b and permit the pressure fluid to exhaust from the main cylinder A thereby causing the molding table B to, at once, fall on to the impact surfaces B^1 and produce the jarring action.
- 10 Simultaneously with the fall of the table B the control rod a^4 also moves downward and once more contacts with the upper end of the pilot valve k and forces same down thereby bringing the circumferential passageway m^3 opposite the exhaust port m^2 thus permitting the fluid pressure under the jarring valve a to escape by means of the port m^1 and exhaust port m^2 when the spring a^2 immediately forces the jarring valve a down on its seat g^1 bringing the various parts into their original position again for repeating the jarring operation. The jarring operation continues as long as the pressure fluid supply is allowed to pass to the pilot valve k by the pipe J and to the jarring valve a by the pipe K .

When the jarring operation is concluded pressure fluid is then admitted to the lifting cylinders C by the pipe I to raise the turn-over table D , from whence it also passes by way of the by-pass H and opening d into the valve chest b thereby locking the jarring valve a during the raising and reversing of the turn-over table D . Fluid is then admitted to the main cylinder A by the pipe K to raise the molding table B to meet the turned over mold and, thereafter, the supply of fluid to the main cylinder is discontinued and the usual exhaust cock, for exhausting fluid from below the main ram, by port e , is opened to allow the table and mold to gradually resume their normal position, or this is allowed to be effected by leakage around the main ram. When the mold is cleared off the molding table B the

turn-over table D is again reversed and the fluid exhausted from the side cylinder C which allows the turn-over table D also to fall to its normal position. When this takes place the jarring valve a is relieved of the fluid pressure in the upper part of the valve chest b and the valve a is then again under normal working conditions.

Having now fully described my invention what I claim and desire to secure by Letters Patent, is:—

1. A molding machine of the jarring type and operated by fluid pressure provided with lifting cylinders and having means, in connection with the jarring valve, for controlling the operation of the same by fluid pressure and means for locking the jarring valve by fluid pressure when desired, said means comprising a pipe leading from the lifting cylinders for conveying fluid pressure to the top of said jarring valve.

2. A molding machine of the jarring type and operated by fluid pressure provided with lifting cylinders and having, in combination with the jarring valve, a pilot valve operated by the fluid under pressure for controlling the action of the jarring valve, and a by-pass leading from the lifting cylinders for admitting pressure fluid to the top of said jarring valve to lock the same.

3. In a device of the character stated, a pilot valve casing having an inlet at its bottom, a pilot valve in said casing having a longitudinal groove in its body, a stop in said casing and adapted to engage the top and bottom terminals of said groove, means for mechanically actuating said pilot valve in a downward direction by the descent of a molding table, a jarring valve casing, a jarring valve therein, said jarring valve casing being open at its bottom or exhaust, and exhaust ports in said casings controlled by a reduced portion of said pilot valve.

4. In a device of the character stated, lifting cylinders, a pilot valve casing having an inlet at its bottom, a pilot valve in said casing having a longitudinal groove in its body, a stop in said casing and adapted to engage the top and bottom terminals of said groove, means for mechanically actuating said pilot valve in a downward direction by the descent of a molding table, a jarring valve casing, a jarring valve therein, said jarring valve casing being open at its bottom for exhaust, and exhaust ports in said casings controlled by a reduced portion of said pilot valve, in combination with a by-pass leading from lifting cylinders for conveying fluid pressure to the top of said jarring valve to temporarily lock the latter.

5. In a device of the character stated, a pilot valve casing having an inlet at its bottom, a pilot valve in said casing having a longitudinal groove in its body, a stop in said casing and adapted to engage the top and

- bottom terminals of said groove, means for mechanically actuating said pilot valve in a downward direction by the descent of a molding table, a jarring valve casing, a jarring valve therein, said jarring valve casing being open at its bottom for exhaust, a spring intermediate the top of said jarring valve and the top of its casings, an adjustable threaded stem for limiting the upward movement of said jarring valve, and exhaust ports in said casings controlled by a reduced portion of said pilot valve.
6. In a device of the character stated, lifting cylinders, a pilot valve casing having an inlet at its bottom, a pilot valve in said casing having a longitudinal groove in its body, a stop in said casing, and adapted to engage the top and bottom terminals of said groove; means for mechanically actuating said pilot valve in a downward direction by the descent of a molding table, a jarring valve casing, a jarring valve therein, said jarring valve casing being open at its bottom for exhaust, a spring intermediate the top of said jarring valve and the top of its casing, an adjustable threaded stem for limiting the upward movement of said jarring valve, and exhaust ports in said casings controlled by a reduced portion of said pilot valve, in combination with a by-pass leading from lifting cylinders for conveying fluid pressure to the top of said jarring valve to temporarily lock the latter.
7. In a device of the character stated, a pilot valve casing having an inlet at its bottom, a pilot valve in said casing and adapted to engage the top and bottom terminals of said groove, means for mechanically actuating said pilot valve in a downward direction by the descent of a molding table, a jarring valve casing, a jarring valve therein, said jarring valve casing being open at its bottom for exhaust, and exhaust ports in said casings controlled by a reduced portion of said pilot valve, in combination with a cup leather piston at one end of said pilot valve and a striker head at the top of said pilot valve and adapted to be actuated by a control rod carried by said molding table.
- 50 8. A molding machine of the jarring type having a molding table, a turn-over table, fluid pressure means for raising the molding table, fluid pressure means for raising the

turn-over table, a jarring valve, means for controlling the operation of the jarring valve by fluid pressure, and means whereby fluid pressure can be admitted to the jarring valve in order to lock the same and thereby prevent the molding table being dropped by the action of said jarring valve while the turn-over table is raised.

9. A molding machine of the jarring type having a molding table, a turn-over table, fluid pressure means for raising the molding table, fluid pressure means for raising the turn-over table, a jarring valve, a pilot valve arranged in combination with said jarring valve and adapted to admit fluid pressure for moving the valve in one direction, resilient means for moving the valve in the opposite direction, and means whereby fluid pressure can be supplied to raise the turn-over table and at the same time be admitted to one end of the jarring valve to lock the same in position.

75 10. A molding machine of the jarring type having a molding table, fluid pressure means for raising the table, a valve for controlling the supply of the fluid pressure and for exhausting the same, a pilot valve for controlling the action of said control valve, said pilot valve being actuated by fluid pressure in one direction and by the molding table in the opposite direction, the combined valves controlling the movements of the molding table.

11. In a device of the character stated, a pilot valve casing having an inlet at its bottom, a pilot valve in said casing having two longitudinal grooves in its body, the grooves being of different lengths, a stop in said casing and adapted to engage the top and bottom terminals of either of said grooves, means for mechanically actuating said pilot valve in a downward direction by the descent of a molding table, a jarring valve casing, a jarring valve therein, said jarring valve casing being open at its bottom for exhaust, and exhaust ports in said casings controlled by a reduced portion of said pilot valve.

In testimony whereof I affix my signature in presence of two witnesses.
